UNITED STATES PATENT OFFICE.

JOHN F. LYONS, OF SEATTLE, WASHINGTON.

DESIGN FOR A GAME-BOARD.

59,850.

Specification for Design.

Patented Nov. 29, 1921.

Application filed August 15, 1921. Serial No. 492,523. Term of patent 7 years.

To all whom it may concern:

Be it known that I, JOHN F. LYONS, a citizen of the United States residing at Seattle, in the county of King and State of Washington, have invented a new, original, and ornamental Design for a Game-Board, of which the following is a specification, reference being had to the accompanying drawings, forming a part thereof.

In the drawings the figure is a plan view of a game board embodying my new and original design.

I claim—

The ornamental design for a game board as shown.

JOHN F. LYONS.
